FORCED-DRAFT AIR SUPPLY AND CONTROL
MEANS FOR FURNACES

Harry P. Katz, Cleveland, Ohio

Application November 20, 1943, Serial No. 511,126

4 Claims. (Cl. 110—72)

1

This invention relates to draft control designed for general use but primarily for coal or wood fired furnaces and boilers intended for domestic use.

It is particularly aimed to provide a force air-draft control capable of automatic operation with a blower thereof by a thermostat, and which control can be permanently attached in the draft opening of the ash-pit door.

It is further aimed to provide a novel force draft control including a twin-blower associated with a novel housing with which both blowers communicate, and which housing is controlled by a novel shutter adapted to open to air inducted by the blower and close automatically when the blower is idle.

It is also aimed to provide a novel housing and means to mount the same, to protect the twin blower and motor against fine coal, dirt and the like.

In addition, I aim to provide a means to enable the firebed to be maintained longer so as to require minimum use of the automatic blower, such means being in the nature of a check damper adjustably controlled as to position and adapted to automatically close as the furnace door through which fuel is supplied, is open. The adjustment of such damper will prevent the furnace from becoming overheated.

Various additional objects and advantages will become apparent and in part be pointed out in the description following taken in connection with accompanying drawings illustrating an operative embodiment.

In said drawings:

Figure 1 is a view of the furnace embodying my improvement;

Figure 2 is an enlarged view taken horizontally through the furnace door and showing the mounting of my improvements;

Figure 3 is a vertical sectional view taken on the line 3—3 of Figure 1; and

Figure 4 is a vertical sectional view taken on the line 4—4 of Figure 2.

Referring specifically to the drawings wherein like reference characters designate like or similar parts, 10 represents a conventional coal or wood furnace which is adapted to be fired through an opening normally closed by a usual door at 11, hinged in place as at 12. Such furnace has an ash-pit door at 13 also hinged in place as at 14, and further has a discharge flue 15 and an air-inlet duct at 16. This duct 16 has pivoted over its open outer end at 17, a check damper 18. Lug 19 is provided on this damper and a screw 20

2

passes loosely through a hole therein and which screw is adjustable as to position through the manipulation of a nut 21 thereon. Attached to the bolt 20 is a chain or other flexible element 21, which is trained over pulleys 22 and 23, suspended from a ceiling 24 above the furnace and leading and being connected to a part of the door 11 such as the operating or latch handle 26. As a result, when the door 11 is opened, the chain 21 will be sufficiently slack to enable the damper 18 to automatically close, while when the door is closed, the chain will be taut and thus the check damper will be automatically opened. Through the adjustment of the bolt 20 by reason of the nut 21 threaded thereon, the check damper is adjustable to the exact extent of opening that is desired at the duct 16 in order to prevent the furnace from overheating, and at the same time aids the firebed in being maintained for the maximum period of time without any other controls such as the automatic draft blower controls as will now be described.

Reverting to the ash-pit door 13, it has the usual draft opening 27 therethrough in which a draft duct 28, in accordance with my invention, is disposed and fastened in any suitable manner. It will be noted that a shutter or damper 31 is pivoted in the duct 28 on a horizontal axis 32, the shutter being of a length to prevent movement past the vertical and also having a weight at 33, whereby the shutter will automatically close in the absence of a draft therethrough.

In connection with the invention, I use a twin blower structure generally designated A. This structure is a unit having an electric motor 33 on whose main shaft 34 are keyed suitable impellers or fans 35, each operating within a casing 36, having a discharge end or pipe 37 tightly but removably bolted to the duct 28 through part 38.

It will be noted that the casings 36 have their intake openings at their outer sides as at 39.

In order to prevent fine coal, dirt, or other foreign matter from affecting the motor 33 and the blowers, and preventing the transmission of undue heat thereto, as well as functioning in supporting the blower structure, I dispose over the same an apron or shield at 40, the same being detachably bolted as at 41 to the casing or frame of door 13. Also, in order to render the mounting of the shield 40 more stable, I provide outwardly extending ears 42 on inward extensions 43 of the shield 40. The ears 42 have openings 44 therethrough which are engaged each by a hook 45,

loosely pivoted as at 46 at opposite sides of the duct 28.

In order to open and close the intake openings 39 of the blowers, to any extent desired, closures 46 are adjustable thereover, being pivotally mounted on the bolts 47 passing therethrough and through the extensions 43 and which have wing-nuts 48 thereon to facilitate manual manipulation.

The motor 33 is preferably under automatic control, that is, control of a thermostat. When the motor operates, it forces a draft by inducing air through the openings 39 into the blowers and discharging it through the outlets 31 into the duct 28 and then into the ash-pit beneath the firebed. It will be realized that the action of the air or draft automatically opens the shutter 31 and that in the absence of such draft, the shutter automatically closes under the action of the weight 33.

It will be realized that the check damper 18 will be automatically closed when the door 11 is opened to refuel the furnace, and that the closing thereof serves to give the natural draft to the furnace and aids in carrying off smoke while refueling.

Various changes may be resorted to provided they fall within the spirit and scope of the invention.

I claim as my invention:

1. In combination with the ash-pit door of a furnace, a forced draft unit mounted thereon in communication with the atmosphere and the interior of the furnace, the unit comprising a duct having one end communicating with the furnace, a blower means associated therewith having an intake communicating with the atmosphere, and shutter means for the duct, biased so as to automatically close in the absence of draft, said shutter means being displaceable to open position in the presence of a draft from the blower means, the blower means having a discharge pipe leading to the duct, and a shield extending from the duct rearwardly and downwardly over the blower means, devices positioning said shield attached adjacent the lower end thereof and to the duct, and a closure mounted on said shield for the intake and adjustable relatively thereto.

2. In combination with the ash-pit door of a furnace, a forced draft unit mounted thereon in communication with the atmosphere and the interior of the furnace, the unit comprising a duct having one end communicating with the furnace, a blower means associated therewith having an intake communicating with the atmosphere, and shutter means for the duct, biased so as to automatically close in the absence of draft, said shutter means being displaceable to

open position in the presence of a draft from the blower means, the blower means comprising a motor and blower elements operated thereby on opposite sides thereof, having discharge pipes communicating with the duct, and a shield extending from the duct over the blowers and motor, said shield having ears, and hooks extending from the duct engaging said ears whereby the shield is retained in position.

- 10 3. In combination with the ash-pit of a furnace, a forced draft unit mounted thereon in communication with the atmosphere and the interior of the furnace, the unit comprising a duct having one end communicating with the furnace, a blower means associated therewith having an intake communicating with the atmosphere, shutter means for the duct biased so as to automatically close in the absence of draft, said shutter means being displaceable to open position in the presence of a draft from the blower means, the blower means comprising a motor and blower elements operated thereby on opposite sides thereof having discharge pipes communicating with the duct, and a shield extending from the duct over the blowers and motor, said shield having ears, elongated elements fastened at opposite ends to the ears and to the duct to retain a lower portion of the shield in position, and closures for the intakes of the blower elements pivoted to the said ears for adjustment to control the closing and extent of opening of the said intakes.

- 20 4. A combination according to claim 2 wherein the intakes have closures pivotally mounted on said ears for adjustment to control the closing and extent of opening of said intakes.

HARRY P. KATZ.
